ORNAMENTAL METAL-WORK PANEL

Leonard M. Logan III, Fort Worth, Tex., assignor to
McKinley Iron Works, Fort Worth, Tex., a partnership

Application May 23, 1957, Serial No. 46,305

Term of patent 14 years

(Cl. D54—2)

FIG. 1

FIG. 2

FIG. 3

FIG. 4

FIG. 5

FIG. 6

Fig. 1 is an elevation of one side of an ornamental metal-work panel embodying my new design;

Fig. 2 is a view of the right-hand edge of Fig. 1;

Fig. 3 is a bottom view of Fig. 1;

Fig. 4 is an elevation of the other side of the panel;

Fig. 5 is a view of the right-hand side of Fig. 4; and

Fig. 6 is a top view looking down on Fig. 4.

I claim:

The ornamental design for an ornamental metal-work panel, as shown.
